UNITED STATES PATENT OFFICE.

EVERETT W. SWARTWOUT, OF WHITE PLAINS, NEW YORK.

UNIFLOW ENGINE.

1,390,398.

Specification of Letters Patent. Patented Sept. 13, 1921.

Application filed June 3, 1916, Serial No. 101,511.

To all whom it may concern:

Be it known that I, EVERETT W. SWARTWOUT, a citizen of the United States of America, residing at White Plains, county 5 of Westchester, State of New York, have invented certain new and useful Improvements in Uniflow Engines, of which the following is a description.

This invention relates to the provision of 10 clearance means in uniflow steam engines and other devices employing inlet valves disposed adjacent the ends of the cylinder for the inflow of the medium and exhaust ports disposed centrally of the cylinder and 15 controlled by the piston for the outflow of the medium.

A principal advantage of engines of the uniflow type as particularly compared with engines of the counterflow type, is the elimination of so-called initial condensation of 20 the steam, that is to say, the avoidance of condensing of a portion of the steam into water, as it enters the cylinder and thereby decreasing the amount of heat available for 25 performing useful work. Such advantageous condition ensues only during the period or periods of continuance of the operating conditions for which any particular uniflow engine is specifically designed, and 30 in practical operation such particular conditions prevail for relatively short periods. The usual causes of departure from the particular operating conditions for which the uniflow engine is designed, are leakage or 35 failure of the condenser parts and variations in temperature of the condenser cooling water, thereby giving rise to a so-called decrease of vacuum in the exhaust belt, whereby an increase in the pressure of the cylinder 40 takes place when the exhaust is closed and a consequent increase of the final compressional pressure and in excess of the initial pressure of the steam. Such excessive compressional pressure causes overheating and 45 possible rupture of the parts of the engine.

According to my invention, there is provided clearance means comprising a plurality of clearance chambers or spaces adapted to be brought into effective communication with the interior of the cylinder and the proper clearance value or total effective clearance determined or regulated to attain 50 the desired smooth working. Such determination or regulation effects the preclusion

of a compression pressure in excess of the 55 initial pressure and is attained by means which is operated or controlled independently of the maximum compressional pressure. Preferably, the communication of the clearance chambers or spaces with the interior 60 of the cylinder is controlled by or in response to the exhaust pressure, whereby variations in the exhaust pressure control the communication of the clearance chamber or chambers at a time in advance of the 65 instant at which the piston reaches the region of its limiting position. The communication of any clearance chamber or space with the interior of the cylinder is usually opened or closed by a valve and such 70 valve may be employed as a valve for opening or closing the communication of all the clearance chambers or spaces in common.

As one preferred form of my invention, I allude to the double acting steam engine of 75 the uniflow or central exhaust type provided with clearance means, preferably disposed at both the head and the frame end of the cylinder, each having a port, and a valve controlling the communication of each port 80 with the clearance proper of the engine. Preferably also the casings of each such valves and the clearance spaces are heated by live steam. The clearance spaces may be 85 of equal clearance value or of unequal clearance values, and in the latter case may be arranged progressively increasing, or progressively decreasing.

It is convenient in engines of the usual 90 capacities to arrange the clearance spaces at any end of the engine in juxtaposed relation and to control the communication between the ports of the same and the clearance proper by a single valve operated in accordance with the objects of this invention.

According to modern steam practice, the initial pressure, *i. e.*, boiler pressure, is maintained substantially constant, and the usual variation is encountered by changes in 100 the exhaust or terminal pressure. Under these circumstances, my invention is particularly advantageous in controlling the clearance spaces in response to variation in exhaust conditions, as by suitable means operated either directly or indirectly in connection with the exhaust.

It will be understood that my invention in

clearance means is also applicable to other forms of fluid machines operating on the uniflow principle, and controlled in connection with the suction or discharge or both, 5 as conditions would require.

Other objects and features of my invention will be more fully set forth in the following detail description and accompanying drawings, in which—

10 Figure 1 is a diagrammatic central sectional elevation showing a form of my invention applied to the head of a uniflow steam engine;

15 Fig. 2 is a side elevation, partly in vertical central section showing my invention applied to the frame end as well as the head of a double acting uniflow steam engine; and Figs. 3, 4, and 5 are detail diagrammatic views showing the clearance valve in different positions.

20 Referring to Fig. 1, the piston 1 is represented in the cylinder 2 at its position of maximum compression. The clearance proper is represented by the space 3 disposed between the head of the piston 1 and the head 4 of the cylinder 2, the clearance proper 3 being exaggerated somewhat as shown in Fig. 1, for the sake of clearness.

25 At a suitable location as in the head 4 is arranged the port 5 adapted to afford communication of the clearance proper 3 with the clearance spaces.

30 In the particular form of my invention indicated in Fig. 1, the clearance spaces are 35 constructed in the form of a main chamber 6 and supplemental chambers 7, 8, 9, controlled by the piston valve 10 disposed within the chamber 6. The piston valve 10 is provided with the forward packing ring 40 11 and the rearward packing ring 12 and with a passage-way portion 13 disposed intermediate the packing rings 11, 12. The passage means shown as one or more perforations 14 extending through the piston 10 45 afford communication between the portions of the chamber 6 on both sides of the piston 10. Such passage means results also in a valve which is balanced for all positions.

40 The chamber 6 is designed in capacity to 50 provide the additional clearance required when the exhaust is varied from condensing condition to exhausting into the atmosphere, or equivalent pressure. As the pressure varies from vacuum toward atmospheric 55 pressure, the piston valve 10 is moved to successively bring into communication with the clearance proper 3 of the cylinder 2 the chambers 7, 8 and 9, in the order named; or in the inverse order for the variation of the 60 pressure from atmospheric toward absolute vacuum. Upon varying the condition of exhausting in a condenser to exhausting into the atmosphere, the piston valve 10 is moved to the position of fully opening the port 5 65 into communication with both portions of

the chamber 6 on the two sides of piston valve 10, but not into communication with any of the clearance spaces 7, 8, 9. Under the condition of slight back pressure in the exhaust region, the piston valve 10 will be 70 moved still farther to open the port of supplemental clearance space 7 into communication with the main clearance space 6, but excluding communication of the supplemental clearances 8, 9. Under increased back 75 pressures, the supplemental clearances 8, 9, and further supplemental clearances if desired, will be progressively brought into effective communication with the clearance proper of the cylinder by similarly increased 80 movement of the piston valve 10, as more fully set forth hereinafter, in relation to Figs. 3, 4 and 5.

85 As one means for effecting these functions, I have shown the following described means automatically controlled in connection with the exhaust region of the engine.

90 The valve stem 18 of clearance valve 10 is shown controlled by the exhaust responsive means, comprising the differential piston 19 fixed to said valve stem 18 and within casing 20. Said differential piston 19 is formed of the head portion 21, made steam-tight with the inner surface of casing 20, and the rearward portion 22 of reduced cross-sectional 95 area, affording the variable pressure space 23 and the pressure area 24 shown as annular in contour. The reduced portion 22 is made steam-tight with the partition ring 25. In the position shown in Fig. 1, the 100 differential piston 19 and accordingly the clearance valve 10, are in their respective extreme positions, restricting the clearance value to the clearance proper of the cylinder. At this point, it will be noted that the 105 cubic capacity of the port 5 and passage portion 13 of the clearance valve 10 enter into the value of the clearance proper of the cylinder.

110 The vacuum pressure controller is shown as a piston 26 mounted in the casing 27, open at one side 28 to the atmosphere, and connected on the opposite side 29 through the passage 30 to the exhaust region 17. The piston 26 is also provided with the adjustable compressional spring 31.

115 Said piston 26 controls the communication of the ports 32, 33 of casing 20 of the differential piston 19 with the exhaust region 17, the boiler and the atmosphere as explained more fully hereinafter. The lower port 32 is connected with the passage 34 leading to the rotary three-way valve 35. Similarly the upper port 33 communicates through passage 36 with another valve space 120 of said three-way valve 35.

125 The passage 37 of the three-way valve 35 opens to the atmosphere. The piping 38 leads to the boiler.

130 On the stem 18 of the plunger valve 10 is

also arranged means for counterbalancing the effectual force applied to said differential piston 19, comprising the weights (four shown), 40, 41, 42, 43, preferably of progressively increasing masses, normally resting on seats 44 afforded by the frame 45, and each weight provided with an opening through which the stem 18 freely passes. The abutment 46 is fixed to frame 45 and the 10 spring 47 is positioned between said abutment 46 and the collar 48, fixed to stem 18. The strength of spring 47, adjusted by any approved means, is made sufficient to overcome the weight of and friction against the 15 stem 18, differential piston 19 and clearance piston 10, and move the collar 48 against weight 40. One such approved adjustment means is indicated in Figs. 1, 3, 4 and 5, showing the cup 46 of spring 47 adjusted by 20 means of screws 46^a.

The springs 49 are preferably employed to serve as buffers and to effect gradual increase in the counterbalancing function, to which end the springs 49 are positioned in 25 intermediate and have their end portions engaging the respective weights 40, 41, 42, 43.

In the positions of the vacuum piston 26 and the differential piston 19 as indicated in Fig. 1, the pressure applied to the 30 vacuum piston 26 may be the minimum for the design of the particular engine shown, say twenty-six inches vacuum running with a condenser, in which case, the differential piston 19 is at its extreme lowest 35 position and the piston valve 10 restricts the port 5 to limit the clearance to the clearance proper of the cylinder. It will be noted that the three-way valve 35, controlled by vacuum piston 26 through link 56 and 40 valve arm 50, under these conditions effects the communication of the passage 34 to atmosphere to cause the atmospheric pressure to be applied to the face 21 of differential piston 19, while the face 24 of reduced 45 area is being subjected to boiler pressure, by reason of the passage 36 being brought by the three-way valve 35 into communication with the passage 38 leading to the boiler. Upon increased pressure at the 50 exhaust region, *i. e.*, under conditions of less vacuum, the vacuum piston 26 will be moved downwardly, causing the movable valve member of three-way valve 35 to be turned (counter-clockwise as viewed in Fig. 1), until the 55 passage 36 will be cut off from connection with the boiler and be brought later in communication with the atmosphere, while at the same time the passage 34 will be cut off from connection with the atmosphere 60 and brought into communication with the passage 51 leading to the exhaust region. Under these conditions, the differential piston 19 will rise under action of the spring 47 modified by the differential pressure on 65 the differential pressure piston 19.

During such upward movement of the differential piston 19, the piston valve 10 is moved upwardly through its casing 6 to the first stage, as is indicated in Fig. 3, of effecting communication of the port 5 of the 70 cylinder 3 with the port 54 of the first clearance chamber 7, then to the stage, as indicated in Fig. 4, of effecting communication of the port 5 with the interior of the casing 6, serving as the main supplemental 75 clearance chamber; then to the stage as indicated in Fig. 5 of effecting communication of the port 5 of the cylinder 3 with the main clearance chamber 6 and the first supplemental clearance chamber 7; then successively to the subsequent stages of effecting communication through the port 5 of the clearance proper of the cylinder 3 with the main clearance chamber 6, the first supplemental clearance chamber 7, together with 85 the additional supplemental chambers 8, 9, etc.

The collar 48 is brought in contact with the lower most weight 40 as the piston valve 10 progresses toward its position corresponding to atmospheric exhaust, as is indicated in Fig. 5; at the stage of atmospheric exhaust, the piston valve 10 has been moved upwardly to its extreme position of effecting communication of the clearance proper 90 through the port 5 of the cylinder 3 with the main clearance chamber 6 and all the supplemental clearance chambers 7, 8, 9, etc.

Further movement of the piston valve 10 will uncover the port 54 of clearance 7 to add 100 the same as an effective clearance value to the main clearance 6 and clearance proper as indicated in Fig. 5, at which stage the first weight 40 will have been fully lifted from its seat 44. Continuing such increased pressure at the exhaust region, the port 53 of 105 clearance 8 and the port 52 of clearance 9 will be successively uncovered and brought into effective communication with the clearances previously brought into operation, including 110 the clearance proper 3 and the main clearance 6.

The maximum clearance, it will be observed, ensues when the exhaust pressure is 115 the maximum for which the device is designed. Preferably the vacuum piston 26 is constructed and its spring 31 adjusted so that under the conditions of the attaining of the degree of vacuum at which the maximum performance with a clearance value of 120 the clearance proper of the device is obtained, the vacuum piston 26 assumes the position indicated in Fig. 1; and under the condition of pressure in the exhaust region approaching more or less atmospheric pressure, the piston 26 will be moved to turn the three-way valve 35 sufficiently to cause a pressure of substantially atmospheric pressure to be 125 applied to the reduced pressure area 24 of differential piston 19 and the pressure of the 130

exhaust region to be applied to the face 21 of said piston 19. As the pressure in the exhaust region exceeds atmospheric pressure, the effective pressure applied to said face 21 will more and more exceed the effective pressure applied to the reduced area 24 of said differential piston, causing said piston 19 and therewith stem 18, to rise until the same becomes balanced by the required number of weights 40, 41, 42, 43 and intermediate springs 49, or equivalent means. Such movement of stem 18 causes the clearance valve 10 to effect the successive addition of the supplemental clearance spaces 7, 8, 9. Reversing the change in pressure conditions assumed above, upon the change in the exhaust region from atmospheric pressure, or excess thereof, to full or partial vacuum, the exhaust piston 26 will ultimately be moved and the three-way valve caused to rotate in the clockwise direction, and cause the exhaust pressure and ultimately the boiler pressure to force the differential piston 19 downwardly, and therewith permit the clearance valve 10 under the force of the weight of the weights 40, 41, 42, 43 to successively cut out the supplemental and main clearance chambers from effective communication with the clearance proper of the cylinder.

When my invention is applied to an engine, it is preferable to incise the main and supplemental clearance means to provide heating the same with the heated medium, as by the casing 55 connected by the passage 55^a as indicated in Fig. 2 with the inlet steam passage of the engine. As indicated in Fig. 1, the head may be thinned at the region of location of the clearance means, to thereby increase the heat radiation between the interior of the cylinder and the interior of the casing surrounding the clearance means.

In Fig. 2, I have indicated an approved type of uniflow engine provided with clearance means embodying my invention at the frame end as well as the head of the cylinder, said clearance means being each automatically controlled by the exhaust by a suitable arrangement such as has been described above in connection with Fig. 1. The above described means when applied to a uniflow steam engine accordingly provides a clearance means which is increased in effective clearance value as the exhaust pressure is increased, due to withdrawal of steam for heating or other purposes. By means of my invention, therefore, the pressure of the steam at the end of the compression stroke will be precluded from exhausting the initial pressure and is maintained substantially equal to the initial pressure, by adjustment of the clearance, in correspondence to each particular exhaust pressure, thereby maintaining the pressure curve of maximum efficiency for the particular engine in question.

When the engine is running continuously

noncondensing or under atmospheric exhaust, the three-way valve 35 may be rendered inoperative by closing the stop valves 70, 71, 72, respectively in the passages 30, 51, 38 and the stop valve 60 in passage 34, and providing the by-pass 61 directly connecting the passage 34 with the exhaust and the outlet passage 62, opening to the atmosphere upon opening its stop valve 63. Under this condition the differential piston 19 is operated directly by the action of the exhaust pressure through the passage 61 and the port 33 connected through the passages 36, 62 with the atmosphere.

And when the engine is run continuously non-condensing, or under other conditions, upon closing the indicated stop-valves 70, 71, 72 respectively in the passages 30, 51, 38 and the stop-valve 60 in passage 34, and by providing the by-pass 61 connecting passage 34 with the exhaust, and the outlet pass 62, opening to the atmosphere upon opening its stop-valve 63, the vacuum piston 26 and the three-way valve may be rendered ineffective and may be omitted if desired.

It will be noted that the proportional volumes of the main and supplemental clearance chambers are determined by the particular characteristics of the engine, or other uniflow device to which my invention is applied.

It will thus be observed that the engine or similar device constructed in accordance with my invention is adapted to operate under a great variety of industrial conditions in which it is desirable for flexibility and efficiency, as desired, to operate with exhaust or discharge pressures which may vary between wide limits, say 26 inches vacuum and say 5 pounds gage back pressure for engines, etc. as will be understood by the art.

When my invention is employed in combination with other types of units which operate on the uniflow principle, and which are not specifically defined in detail hereinabove, my invention is properly operated therewith by connection with either the suction line or the discharge line or both, or with any other suitable part of the uniflow unit, to effect the desired variations or regulation of capacity and power required, and to attain the desired efficiency as may be determined by the particular circumstances.

From the above, it will be seen that I have devised a clearance means which positively effects the desired regulation of clearance value applicable to all types of units operating on the uniflow principle. I have also disclosed positive means for automatically attaining such desired regulation of clearance.

Whereas I have described my invention by reference to specific forms thereof, it will

be understood that many changes and modifications may be made without departing from my invention as defined by the appended claims.

5. I claim.

1. The combination with a source of fluid compressed to a substantially constant pressure, of a uniflow device communicating with said source, said uniflow device comprising a cylinder and a piston reciprocable within said cylinder and means for precluding compressional pressure within said cylinder in excess of said constant pressure, said precluding means including a clearance 10 means comprising a plurality of clearance chambers, means for controlling the communication of said clearance means with the interior of said cylinder and exhaust pressure responsive means controlling said 15 controlling means.

2. The combination with a source of fluid compressed to a substantially constant pressure, of a uniflow device communicating with said source, said uniflow device comprising a cylinder and a piston reciprocable within said cylinder and means for precluding compressional pressure within said cylinder in excess of said constant pressure, said precluding means including a clearance 20 means comprising a plurality of clearance chambers, and means for controlling the communication of said clearance chambers successively additively with the interior of said cylinder, said last-named 25 means being responsive to variations of the exhaust fluid pressure.

3. The combination with a source of fluid compressed to a substantially constant pressure, of a uniflow device communicating 30 with said source, said uniflow device comprising a cylinder and a piston reciprocable within said cylinder and means for precluding compressional pressure within said cylinder in excess of said constant pressure, said precluding means including a clearance 35 means comprising a plurality of clearance chambers, and means for controlling the communication of said clearance means successively additively and subtractively with the interior of said cylinder, said last-named means being responsive to the variations 40 of said exhaust fluid pressure.

4. The combination with a source of fluid compressed to a substantially constant pressure, of a uniflow device communicating 45 with said source, said uniflow device comprising a cylinder and a piston reciprocable within said cylinder, and means for precluding compressional pressure within said cylinder in excess of said constant pressure, said precluding means including a clearance 50 means comprising main and supplementary clearance chambers, and means for controlling the communication of said clear-

ance chambers successively with the interior 65 of said cylinder, said last-named means being responsive to variations of the exhaust fluid pressure.

5. The combination with a source of compressed fluid, of a uniflow device having 70 its inlet communicating with said source, said uniflow device comprising a cylinder and a piston reciprocable within said cylinder and means for precluding compressional pressure within the said cylinder in 75 excess of the inflow fluid pressure, said precluding means including a plurality of clearance chambers, means for controlling the communication of said clearance chambers successively additively with the interior of 80 said cylinder, and means responsive to variations of the exhaust fluid pressure and for controlling said communication controlling means.

6. The combination with a source of fluid 85 compressed to a substantially constant pressure, of a uniflow device communicating with said source, said uniflow device comprising a cylinder and a piston reciprocable within said cylinder and means for precluding compressional pressure within said cylinder in excess of said constant pressure, said precluding means including a clearance 90 means comprising clearance chambers respectively of different clearance values, 95 means for controlling the communication of said clearance chambers successively additively and subtractively with the interior of said cylinder and means responsive to variations of the exhaust fluid pressure for controlling 100 said communication controlling means.

7. The combination with a source of compressed fluid, of a uniflow device provided 105 with a cylinder, and a piston reciprocable in said cylinder, clearance means comprising a plurality of clearance elements, and common means for controlling communication of said clearance elements successively with the interior of said cylinder, said common 110 communication controlling means comprising a device responsive to variations of the exhaust pressure and operating independently of the speed of operation of the uniflow device.

8. The combination with a source of compressed fluid, of a uniflow device and provided with a cylinder provided with inlet valves adjacent its opposite ends and an exhaust port disposed intermediate said cylinder ends and provided further with a piston reciprocated in said cylinder, clearance means comprising a plurality of clearance elements, and common means for controlling the communication of said clearance elements successively with the interior of said cylinder, said last-named means being responsive to variations of the exhaust fluid 125

pressure and independently of the speed of operation of said uniflow device for controlling said common communication means.

9. The combination with a source of compressed fluid, of a uniflow device provided with a cylinder having inlet ports disposed adjacent its opposite ends and an exhaust port substantially central of said cylinder ends and provided further with a piston reciprocated in said cylinder, of clearance means comprising a main chamber, supplemental chambers having ports opening into said main chamber, a valve disposed in said main chamber controlling the successive opening and closing of said ports and means responsive to variations of the exhaust fluid pressure for controlling said valve.

10. The combination with a source of compressed fluid, of a uniflow device provided with a cylinder provided with inlet valves disposed adjacent its ends and an exhaust port disposed substantially centrally of said cylinder ends and provided further with a piston reciprocated in said cylinder, of clearance means comprising a main chamber, supplemental chambers and a piston valve controlling the successive communication of said supplemental chambers with said main chamber and means responsive to variations of the exhaust fluid pressure and independently of the speed of operation of said uniflow device for controlling said valve.

11. The combination with a pressure device employing a compressible fluid and provided with a cylinder and a piston reciprocated in said cylinder, of clearance means comprising a main chamber, supplemental chambers communicating with said main chamber, a valve controlling the communication of said supplemental chambers with said main chamber and means responsive to the pressure at the exhaust region of the device controlling said valve.

45 12. The combination with a source of compressed fluid, of a uniflow device and provided with a cylinder provided with an inlet, a piston reciprocated in said cylinder, an exhaust port controlled by said piston and means controlling said inlet, clearance means comprising a main chamber, supplemental chambers respectively having ports opening into said main chamber, a common valve controlling said ports and means responsive to variations of the exhaust pressure of said fluid for varying the position of said valve.

60 13. The combination with a source of compressed fluid, of a uniflow device provided with a cylinder and a piston reciprocated in said cylinder, clearance means comprising a plurality of clearance elements and means for cutting in and out successively said clearance elements, said last named means including means responsive to

variations of the exhaust fluid pressure and independently of the speed of operation of said uniflow device for controlling said clearance means.

14. The combination with a source of compressed fluid, of a uniflow device provided with a cylinder having an inlet, a piston reciprocable therein, an exhaust port controlled by said piston and means controlling said inlet, a plurality of clearance chambers having spacially related ports, balanced valve means controlling said ports including means for balancing said valve at its different positions and means responsive to variations of the exhaust fluid pressure controlling said valve means.

15. The combination with a source of compressed fluid, of a uniflow device provided with a cylinder and a piston reciprocable therein, of a plurality of clearance chambers having spacially related ports, means for controlling said ports, a differential piston controlling said port controlling means and means responsive to variations of the exhaust fluid pressure for controlling said differential piston.

16. The combination with a uniflow device employing a compressible fluid and provided with a cylinder and a piston reciprocable therein, said cylinder being provided with inlet and exhaust ports, of a plurality of clearance chambers having spacially related ports, a valve controlling said ports, a differential piston controlling said valve, fluid passage means leading to the effective surfaces of said differential piston and multiport means responsive to variations of the exhaust fluid pressure for controlling said fluid passage means.

17. The combination with a pressure device employing a compressible fluid and provided with a cylinder and a piston reciprocable therein, of a plurality of clearance chambers having spacially related ports, a valve controlling said ports, a differential piston controlling said valve, passages leading to the effective surfaces of said differential piston, multiport means controlling said passages and a plurality of balancing elements for said differential valve.

18. The combination with a pressure device employing a compressible fluid and provided with a cylinder and a piston reciprocable therein, of a plurality of clearance chambers having spacially related ports, a valve controlling said ports, a differential piston controlling said valve, passages leading to the effective surfaces of said differential piston, a plurality of weights and means for successively connecting said weights with said differential piston.

19. The combination with a pressure device employing a compressible fluid and provided with a cylinder and a piston recipro-

- cable therein, of a plurality of clearance chambers having spatially related ports, a valve controlling said ports, a differential piston controlling said valve, passages leading to the effective surfaces of said differential piston, a plurality of weights, and means for successively connecting and disconnecting said weights with and from said differential piston.
- 10 20. The combination with a uniflow device having a cylinder, a piston reciprocable within said cylinder and a discharge outlet, of a clearance chamber, means controlling the communication of said chamber with said cylinder, a differential piston controlling said controlling means, a set of passages leading to the effective faces of said differential piston, a second set of passages connected with said discharge outlet and the atmosphere, and a multiport valve for connecting and disconnecting said two sets of passages.
21. The combination with a source of compressed fluid, of a uniflow device provided with a cylinder and a piston reciprocated in said cylinder, clearance means comprising a plurality of clearance elements and fluid pressure balanced means for controlling the communication of said clearance elements successively with the interior of said cylinder, said controlling means being responsive to variations of the exhaust pressure.
22. The combination with a source of compressed fluid, of a uniflow device provided with a cylinder and a piston reciprocated in said cylinder, clearance means comprising a plurality of clearance elements, fluid pressure balanced means for controlling the communication of said clearance elements successively with the interior of said cylinder, and means for operating said fluid pressure balanced means, said operating means being responsive to variations of the exhaust pressure.
- 45 23. The combination with a source of compressed fluid, of a uniflow device provided with a cylinder and a piston reciprocated in said cylinder, clearance means comprising a plurality of clearance elements, fluid pressure balanced means for controlling the communication of said clearance elements successively with the interior of said cylinder, and exhaust fluid pressure responsive means for operating said fluid pressure balanced means.
- 50 24. The combination with a source of compressed fluid, of a uniflow device provided with a cylinder and a piston reciprocated in said cylinder, clearance means comprising a plurality of clearance elements, pressure balanced means for controlling the communication of said clearance elements successively with the interior of said cylinder, and means responsive to pressure variations in the exhaust of said cylinder for operating said pressure balanced means.
- 55 25. The combination of a source of steam supply of substantially constant pressure, of a uniflow engine provided with a cylinder, an inlet for said cylinder, controlling means for said inlet, a piston reciprocable within said cylinder and exhaust ports controlled by said piston, of means for maintaining the compressional pressure within the said cylinder substantially equal to the initial pressure, but precluding the rise of the compressional pressure in excess of the initial pressure notwithstanding variations of the exhaust pressure, said compressional pressure maintaining means comprising a plurality of clearance elements, fluid pressure balanced means for controlling the communication of said clearance elements successively with the interior of said cylinder and means for operating said fluid pressure balanced means in response to variations of the exhaust pressure and independently of the speed of operation of said uniflow engine.
- 60 26. The combination of a source of steam supply of substantially constant initial pressure, of a uniflow engine provided with a cylinder, an inlet for said cylinder, controlling means for said inlet, a piston reciprocable within said cylinder and exhaust ports controlled by said piston, of means for maintaining the compressional pressure within the said cylinder substantially equal to the initial pressure but precluding the rise of the compressional pressure in excess of the initial pressure notwithstanding variations of the exhaust pressure, said compressional pressure maintaining means comprising a plurality of clearance elements, a differential piston controlling the communication of said clearance elements with the interior of said cylinder and means controlling said differential piston in response to variations of the exhaust pressure and independently of the speed of operation of said uniflow engine.

In testimony whereof I have signed this specification.

EVERETT W. SWARTWOUT.
